Inventor:
Frederick W. Sanguinet
By Knight, Esq.
Atty. P.

UNITED STATES PATENT OFFICE.

FREDERICK W. SANGUINET, OF ST. LOUIS, MISSOURI.

FILE FOR PACKAGES OF LETTERS.

SPECIFICATION forming part of Letters Patent No. 224,230, dated February 3, 1880.

Application filed May 26, 1879.

To all whom it may concern:

Be it known that I, FREDERICK W. SANGUINET, of the city of St. Louis, in the State of Missouri, have invented a certain new and useful Improvement in Files for Packages of Letters, &c., of which the following is a full, clear, and exact description, reference being had to the accompanying drawings, forming part of this specification.

10 My invention consists in a direction plate or piece for packages of letters, &c., passing through the mail, and which is provided with a number of hooks placed in pairs, with their points or end pointing toward each other, for 15 the holding of elastic bands that serve to hold the letters in the package, and also to hold the direction-piece flat down upon the top of the package.

In the drawings, Figure 1 is a perspective view of my improvement. Fig. 2 is a transverse section through one of the bands. Fig. 3 is a section showing a pair of hooks in side view, formed of one piece of wire; and Fig. 4 is a top view of a modification shown in 25 Fig. 3.

A is the direction plate, board, or piece, upon which may be a paper or other label, B, with the destination of the package C printed or otherwise marked upon it. This board or 30 piece A forms one face of the package or bunch of letters or papers. It may be made of mill-board, leather, wood, or any suitable material.

There may be any number of the bands D 35 D'. Two transverse bands, D, and one longitudinal band, D', are shown. These bands are secured to the outer face of the direction-piece A by hooks or holders E F. The hooks or 40 holders E F have heads or projecting points b, and are placed in pairs, with the points b toward each other, a sufficient space being left between the points for the edgewise insertion of the band between them. After inser-

tion the band is spread out flat upon the face of the direction-piece A, its edges being held 45 by the two hooks E and F.

The hooks or holders are of any suitable construction to hold the edges of the band in such a manner as to prevent its accidental detachment from the piece A, and to allow of 50 the endwise adjustment in the holders of such bands as they are stretched or contracted by the insertion or removal of the bunch of letters or other papers.

I have shown the holders E and F with flat 55 heads, or formed of wire bent into suitable form for the described purpose; but I do not confine myself to any precise form or material. They are riveted fast to the piece A, or attached in any other proper manner. 60

It will be seen that there is a space, e, between the two hooks of each pair E F, to allow the introduction of the band D or D'. Such provision is necessary because the elastic bands are liable to break after they have been used 65 for a time, and must be replaced by others.

In Fig. 1 is shown a pair of hooks, E F, formed of wire, and in Figs. 3 and 4 is shown a modification, in which the hooks E F are formed upon the ends of a single wire passed 70 through the piece A in the form of a staple, the ends E F being lapped past each other over the band D, as shown.

I claim as my invention—

The direction-clip herein described, consisting of the plate A, hooks or holders E F; arranged in pairs and projecting upwardly from the face of said plate, and having the projecting portions b turned toward each other, and the elastic band or bands D, substantially as 80 and for the purpose set forth.

FREDERICK W. SANGUINET.
